Albert F. Lehmann, Detroit, Mich., assignor to Sesco
Incorporated, Detroit, Mich., a corporation of Michigan

Filed Jan. 20, 1958, Ser. No. 49,298

Term of patent 14 years

(Cl. D54—14)

Fig. 2

Fig. 1 is a front perspective view taken from the left end of a centering reel unit for coiled sheet metal, embodying my new design; and

Fig. 2 is a rear perspective view taken from the left end thereof.

The right end, and the inner surface of the housing not shown, being substantially the same as the left end and inner surface shown.

The dominant features of my design reside in the full-line portions of the drawing.

I claim:

The ornamental design for a centering reel unit for coiled sheet metal, substantially as shown and described.
